UNITED STATES PATENT OFFICE

IVAN ROČIĆ, OF NEW YORK, N. Y.

DESIGN FOR A BUREAU OR THE LIKE

Application filed April 11, 1931. Serial No. 39,441. Term of patent 14 years.

To all whom it may concern:

Be it known that I, IVAN Ročić, a citizen of the Kingdom of Croatia, Yugoslavia, and a resident of the city of New York, county of New York, and State of New York, have invented a new, original, and ornamental Design for a Bureau or the like, of which the following is a specification, reference being had to the accompanying drawings, forming part thereof.

I claim:

The ornamental design for a bureau or the like, as shown.

IVAN ROČIĆ.
